UNITED STATES PATENT OFFICE.

WILLIAM LAMBERT, OF EAST POINT, GEORGIA.

AMUSEMENT DEVICE.

Application filed July 20, 1923. Serial No. 652,767.

To all whom it may concern:

Be it known that I, WILLIAM LAMBERT, a citizen of the United States, residing at East Point, in the county of Fulton and State of Georgia, have invented a new Amusement Device, of which the following is a specification.

This invention relates to amusement devices, and particularly to the type of device 10 wherein a plurality of targets mounted in spaced relation in a suitable plane are adapted to be operated by missiles thrown at and engaging with said targets.

An object of the invention resides in providing a device of the above character, 15 wherein a plurality of targets are mounted in a frame, simulating hens setting, which are adapted for operation when engaged by a missile thrown at the target to display an egg, to simulate a hen laying an egg.

Another object of the invention resides in providing a device of the character above referred to having a frame provided with a plurality of spaced parallel bars arranged 25 one upon the other with respect to the horizontal plane of the device, on which are mounted a plurality of targets for rearward and downward swinging movement when engaged by missiles thrown at the target for 30 lowering an object simulating an egg and normally concealed behind the target and bar below the respective bar to simulate a hen laying an egg.

The invention also comprehends other objects and improvements in the details of 35 construction and arrangement of parts which are more particularly pointed out in the following description and claims, directed to a preferred form of the invention, 40 it being understood, however, that various changes in the size, structure and arrangement of these parts may be made without departing from the spirit and scope of the invention as described and claimed.

45 In the drawing, forming a part of this application:

Figure 1 is a perspective view of the frame member carrying the target, and forming the subject matter of this invention.

50 Figure 2 is a vertical sectional view through one of the bars and targets, showing the same in a position during operation by a missile engaging the same for displaying the egg.

55 Figure 3 is a sectional view, similar to

Figure 2, showing the target in a normal position with the egg hidden behind the target and bar.

The target carrying frame is indicated generally at 1, which includes a plurality of main uprights 2, connected together at their upper ends by a plurality of horizontal members 3, while at the lower forward end of the frame is arranged a wall portion 4, connecting the forward uprights 2, and at the top portion of which is mounted a counter 5 for receiving the missiles to be thrown at the target. A pair of bars 6 extend rearwardly from the counter portion 5 and the lower end portions of the uprights 2, for connection with the forward of a plurality of pairs of supplemental uprights 7, the pairs of which are arranged in spaced relation, and which are of successively increased length progressing rearwardly of the frame, as clearly illustrated in Figure 1 of the drawings. The rear pair of supplemental uprights 7 are connected by side members 8 at the upper ends to the rear uprights 2 of the main frame. The uprights 80 of each pair of supplemental uprights are connected at their upper ends by bar members 9, which form target supports, and by reason of the pairs of uprights being of increased length as they progress rearwardly of the frame, each succeeding bar will be elevated in parallel spaced relation, above the preceding bar, and will have the relation as indicated clearly in Figure 1 of the drawings.

A plurality of targets 10 are mounted on the supporting bar 9, in spaced relation as illustrated in Figure 1, and each target simulates a hen setting. Each target is hingedly connected to its respective supporting bar 9 by suitable spring hinges 11, which will normally maintain the target in upright position on the bars, as illustrated in Figure 3, but which will permit rearward and downward swinging movement of the target relative to the bar for a purpose which will presently appear.

A rod member 12 is provided with a bevelled end 13, hingedly connected as indicated at 14, with the upper rear side of its respective targets, so that the bevelled end will engage the rear side of the target when the same is in upright position and cause the rod member to assume an inclined position as shown in Figure 3. A flexible mem-

ber 15 is connected to the lower end of the rod 12 and carries at its lower end an object 16 simulating an egg.

In using this amusement device, it will be seen that upon throwing a missile at one of the targets carried by the frame, if the missile would hit the target with sufficient force to overcome the tension of the spring hinge 11, a backward and downward swinging movement of the target would be effected, as illustrated in Figure 2, following which the rod 12 will swing on its hinge 14 and permit the lowering of the egg 16 below the horizontal plane of the bar 9, for displaying the egg to the view of the party throwing the missile and simulating a hen laying an egg. The spring hinge 11 will subsequently operate to return the target 10 from the position shown in Figure 2, to its normal position, as illustrated in Figure 3, at which time the inclined relation of the rods 12 together with the movement of the target 10 will raise the egg 16 so that it will be normally hidden behind the bar 9, the target and bar hiding both the egg and the supporting connection therefor.

It will be seen from the foregoing description that a relatively simple and novel form of amusement device has been provided, at which missiles may be thrown, so that upon striking one of the targets, it will effect the simulation of a hen laying an egg.

What is claimed is:

1. An amusement device comprising a frame having a plurality of spaced parallel bars arranged one above the other relative to a horizontal plane, a plurality of targets hingedly mounted on the bar in spaced rela-

tion and normally projecting upwardly from the bar, each target simulating a hen setting, an element simulating an egg for each target, a flexible connection between each egg and the back of the corresponding target, normally holding the egg concealed behind said target and bars, whereby when a missile thrown at a target hits the same, the target will swing on a hinge and lower the egg to view below the bar, for simulating a hen laying an egg. 40

2. An amusement device comprising a frame having a plurality of spaced bars arranged one above the other relative to a horizontal plane, a plurality of targets simulating hens setting hingedly mounted on the bars in spaced relation and normally projected upwardly therefrom, an element simulating an egg, a rod having a bevelled end portion hingedly connected to the rear side of each target, so that the bevelled face of the rod will engage the rear side of the target in the upright position thereof, and a flexible connection between the eggs and the lower end of the rod, whereby in the upright relation of the target, the rods will have an inclined relation for supporting the eggs behind the bars and targets to conceal the same from view, and said targets will be caused to have a backward and downward swinging movement on the hinges when struck by a missile for permitting a movement of the rod and flexible connection relative to the targets and bars so that the eggs will be displayed below the bars for simulating hens laying eggs. 50 55 60 65 70
